DRINK MIXER

Filed Feb. 19, 1923

FIG. 1

FIG. 2

Inventor:
Chester H. Beach
by Sheridan Jones and Sheridan *Atty's*

UNITED STATES PATENT OFFICE.

CHESTER H. BEACH, OF RACINE, WISCONSIN, ASSIGNOR TO WISCONSIN ELECTRIC COMPANY, A CORPORATION OF WISCONSIN.

DRINK MIXER.

Application filed February 19, 1923. Serial No. 618,825.

To all whom it may concern:

Be it known that I, CHESTER H. BEACH, a citizen of the United States, residing at Racine, in the county of Racine and State of Wisconsin, have invented certain new and useful Improvements in Drink Mixers, of which the following is a specification.

My invention relates to improvements in drink mixers, such, for example, as are used 10 on soda fountains.

One of the objects of the invention is to provide an electrically driven drink mixer in which the current is switched on by mechanism actuated by the glass or shaker when 15 it is placed on the supporting stand, and is switched off when the receptacle is lifted therefrom.

Another object is to provide an appliance of this character in which the receptacle is 20 firmly held in position while the motor is running.

A further object is to provide a device of this character which is convenient to operate, and which may be kept in clean, sanitary 25 condition without special effort.

In the accompanying drawings I have illustrated one embodiment of the invention.

Figure 1 is an elevation of the drink mixer;

Fig. 2 is a partial sectional elevation on the line 2—2 of Fig. 1; and

Fig. 3 is an elevation, partly in section, of the switch-actuating mechanism.

The device comprises a suitable base 1, supporting a vertical standard 2. The base has a plurality of legs which support the standard in elevated position, with sufficient space beneath to readily clean the slab or table on which the legs rest. At the upper 40 end of the standard is a housing 3, in which is mounted a switch 4, having an actuating stem 5. This switch may be of any suitable construction, and is preferably a switch of standard form now on the market. It is actuated by a lever 6, in the form of a rod or wire, which is pivotally mounted on a small shaft 7 with its upper end passing through a hole in said stem. The lower end 8 of the lever is bent so as to engage the inner rim 50 of the glass or shaker and be actuated thereby, as hereinafter described. A coiled spring 9 surrounds the shaft 7, one of its ends 10 bearing against an adjacent part of the housing 4, the other end 11 engaging the upper part of the lever 6 and normally hold-

ing the same in the full line position shown in Fig. 3, in which position the circuit is open. When said lever is moved to dotted position the circuit is closed. An electric motor 12 is secured to the switch housing 4, 60 by means of a pair of extensions 13 and by screws or other fastening means 14. The agitator rod 15 depends from the armature shaft, and has an agitator 16 at the lower end thereof.

A pair of guide rods 17 pass through openings in a pair of small brackets 18 projecting from the switch housing, and have their lower ends secured to a ledge or supporting plate 19, the latter being clamped 70 between the base and the standard. The projecting end of this ledge serves as a support for the glass or whatever other receptacle may contain the liquid to be mixed. The guide rods 17 are inclined slightly, as 75 shown in Fig. 1. In placing the tumbler on the supporting ledge 19, the upper rim thereof is slid upwardly along said guide rods until the base of the tumbler is high enough to be moved inwardly against said 80 guide rods and to rest on said ledge. During this upward movement the bent lower end 8 of the pivoted lever is received within the tumbler, the continued upward movement forcing said lower end to the right 85 from the position shown in Fig. 3, against the action of the spring 10. This actuates the switch, turning on the current and starting the motor. The spring-pressed lever 8 also serves to hold the glass firmly against 90 the guide rods 17, thereby preventing it from slipping off its support 19. The receptacle is removed by first pulling it slightly away from the standard 2 to slip its lower end off its supporting ledge, after which it is lowered, thereby permitting the lever 8 to spring 95 back to initial position, opening the circuit, and stopping the motor.

The device is readily operated by one hand, as will be seen, as it is necessary simply to place the glass on the support and remove it in order to effect the operation of the device. Obviously, glasses of different heights may be used.

I claim:—

1. A drink mixer comprising a standard, a motor supported thereby, an agitator rod depending from said motor, a switch also carried by said standard, a horizontal support for a receptacle, a guide to be engaged 100

- by the side of said receptacle when raised onto said support, a pivoted member depending into said receptacle and moved thereby as said receptacle is being lifted to its position on said support, and connections between said member and said switch, whereby the latter is actuated by the positioning or withdrawal of said receptacle on the supporting standard.
- 10 2. In a drink mixer, a supporting ledge, a pair of inclined rods extending upwardly therefrom in nearly vertical position, and a rod extending downwardly between said first-mentioned rods and arranged to engage the inside of a receptacle to hold the latter against said first-mentioned rods and prevent it from slipping from said ledge when raised thereon.
- 15 3. In a drink mixer, a supporting ledge for a receptacle, a nearly vertical guide member extending upwardly therefrom, a pivoted arm arranged above said ledge, said arm having a portion sufficiently above said ledge to exceed the height of any receptacle to be used therewith, the lower end thereof projecting downwardly enough to be received within the shortest receptacle to be used therewith, a switch controlled by the said member, and a motor for stirring the contents of said receptacle and having a circuit controlled by said switch.
4. A drink mixer comprising a base, a standard thereon, a switch at the upper end of said standard, a bracket adjacent said switch, an electric motor supported by said bracket, a vertical agitator stem depending from said motor, a narrow ledge carried by said base beneath the end of said agitator and to one side thereof, inclined guide members extending from said ledge to said bracket, a switch-actuating arm pivoted on said bracket, one end engaging said switch and the other end projecting downwardly into the space occupied by a receptacle to be supported on said ledge, and a spring normally impelling said member in a direction to hold said receptacle against said guide members and to hold said switch in position to maintain the motor circuit open.
- 20 25 In testimony whereof, I have subscribed my name,

CHESTER H. BEACH.

- by the side of said receptacle when raised onto said support, a pivoted member depending into said receptacle and moved thereby as said receptacle is being lifted to its position on said support, and connections between said member and said switch, whereby the latter is actuated by the positioning or withdrawal of said receptacle on the supporting standard.
- 5 10. 2. In a drink mixer, a supporting ledge, a pair of inclined rods extending upwardly therefrom in nearly vertical position, and a rod extending downwardly between said first-mentioned rods and arranged to engage the inside of a receptacle to hold the latter against said first-mentioned rods and prevent it from slipping from said ledge when raised thereon.
- 15 3. In a drink mixer, a supporting ledge for a receptacle, a nearly vertical guide member extending upwardly therefrom, a pivoted arm arranged above said ledge, said arm having a portion sufficiently above said ledge to exceed the height of any receptacle 20 to be used therewith, the lower end thereof projecting downwardly enough to be received within the shortest receptacle to be used therewith, a switch controlled by the said member, and a motor for stirring the contents of said receptacle and having a circuit controlled by said switch.
4. A drink mixer comprising a base, a standard thereon, a switch at the upper end of said standard, a bracket adjacent said switch, an electric motor supported by said bracket, a vertical agitator stem depending from said motor, a narrow ledge carried by said base beneath the end of said agitator and to one side thereof, inclined guide members extending from said ledge to said bracket, a switch-actuating arm pivoted on said bracket, one end engaging said switch and the other end projecting downwardly into the space occupied by a receptacle to be supported on said ledge, and a spring normally impelling said member in a direction to hold said receptacle against said guide members and to hold said switch in position to maintain the motor circuit open.
- 25 5. In testimony whereof, I have subscribed my name,

CHESTER H. BEACH.

50

Certificate of Correction.

It is hereby certified that in Letters Patent No. 1,579,590, granted April 6, 1926, upon the application of Chester H. Beach, of Racine, Wisconsin, for an improvement in "Drink Mixers," an error appears in the printed specification requiring correction as follows: Page 1, line 92, beginning with the word "The" strike out all to and including the word "off" in line 94, and insert instead *The receptacle is removed by first pulling its lower end slightly away from the standard 2 to slip it off*; and that the said Letters Patent should be read with this correction therein that the same may conform to the record of the case in the Patent Office.

Signed and sealed this 11th day of May, A. D. 1926.

[SEAL.]

M. J. MOORE,
Acting Commissioner of Patents.
